Primary Examiner — Janice Hallmark*(74) Attorney, Agent, or Firm* — McGarry Bair PC**(57) CLAIM**

The ornamental design for a ceiling fan blade iron, as shown and described.

DESCRIPTION

FIG. 1 is a bottom perspective view of a ceiling fan blade iron in the environment of a ceiling fan, showing my new design;

FIG. 2 is a top perspective view of the blade iron of FIG. 1;

FIG. 3 is a top view of the blade iron of FIG. 1;

FIG. 4 is a bottom view of the blade iron of FIG. 1;

FIG. 5 is a front side view of the blade iron of FIG. 1;

FIG. 6 is a rear side view of the blade iron of FIG. 1;

FIG. 7 is a left side view of the blade iron of FIG. 1; and,

FIG. 8 is a right side view of the blade iron of FIG. 1.

Portions of the ceiling fan blade iron and ceiling fan environment shown in broken lines form no part of the claimed design.
